FOREIGN PATENT DOCUMENTS

CN 201005349 1/2008

Primary Examiner — Mary Ann Calabrese
Assistant Examiner — Sloan Rozin(74) *Attorney, Agent, or Firm* — Warner Norcross & Judd LLP(57) **CLAIM**

We claim the ornamental design for a hospital bassinet, as shown and described.

DESCRIPTION

FIG. 1 is a front perspective view of a hospital bassinet of the present disclosure, a rear perspective view of the hospital bassinet is a mirror image of this illustrated view; FIG. 2 is a front elevational view thereof, a rear elevational view is a mirror image of this illustrated view; and, FIG. 3 is a side view thereof.
The broken line showing of elements on the hospital bassinet illustrate portions of the article and form no part of the claimed design.
